FLUID SPEED-GOVERNING MECHANISM.

1,237,631.

Specification of Letters Patent. Patented Aug. 21, 1917.

Application filed January 24, 1916. Serial No. 74,040.

To all whom it may concern:

Be it known that I, THEODORE GENSMER, a citizen of the United States, and a resident of Minneapolis, Minnesota, have invented 5 a new and useful Improvement in Fluid Speed-Governing Mechanism, of which the following is a specification.

This invention relates generally to fluid speed governing mechanism in which the 10 rotations of a drive member are transmitted in variable speeds to a driven member. The drive member in most cases is rotated directly by a prime mover such as a gas-engine or electric motor, and the driven member 15 connects with the traction wheels or other element from which the power is taken off.

The main object of my invention is to provide an improved form of speed governing mechanism, in which the speed of the 20 driven member may be varied from zero to maximum, and this accomplished without the use of either sliding, planetary or friction gears. It will be apparent that because the transmission can be reduced to zero, the 25 device will also serve as a clutch. Another object of my invention is to provide an absolutely noiseless transmission mechanism, and also a convenient means for controlling the same.

30 In the accompanying drawings:

Figure 1 is a side elevation of my device, part being shown in section;

Fig. 2 is a diametrical section of one of the pistons;

35 Fig. 3 is a plan view of the piston shown in Fig. 2; Fig. 4 is a sectional view showing a preferred form of piston valve operating mechanism; Fig. 5 is a plan view of the valve and valve stem shown in Fig. 4, and 40 Fig. 6 is a fragmental side elevation of the yoke connecting the opposed pistons.

In the construction shown in these drawings, α represents a drive shaft provided with a crank b and end k . Said shaft is 45 mounted in a bearing c , which is supported by the transverse channel member d of the supporting frame. A driven shaft e is mounted in a bearing f , the latter being supported by the channel member g . The 50 shafts α , e are journaled in longitudinal alinement and the transmission mechanism of my invention is adapted to connect the two. Rigidly mounted on the shaft e is a hub l , bearing spider arms h which support 55 the radial cylinders i , which are shown as

located diametrically opposite each other. A hub j and spider arms are integrally formed with the cylinders i , and the shaft α is rotatably mounted in the hub j . The extreme end k of the shaft α is rotatably 60 mounted in the hub l adjacent the end of the shaft e . The cylinders i are provided at opposite ends with the fluid-tight stuffing boxes m , n . Pistons o , reciprocable within said cylinders, are connected by a rigid piston rod p , the latter being provided at its midway point with a lateral slotted yoke q , in which slot the crank b has a bearing. It will thus be seen that the revolutions of the shaft α will reciprocate the piston rod p so 65 as to move the pistons o always in the same direction. The pistons o are provided with longitudinal ports r (see Fig. 2) and adjacent the outer face of said piston is a plate s , provided with port holes t , adapted to cover 70 the ports r when said plate is rotated. The plate s is rotatable with respect to the piston, but has no longitudinal movement relative thereto, being held in place by a spanner nut u , which is adapted to thread into a 75 tapped recess of said piston. The nut u is provided with ports v , which are in alinement with the ports r , and when the plate s has been rotated so as to bring the ports t in alinement with the ports r , v , fluid will 80 readily bypass from one end of the cylinder to the other. Piston rings are inserted between the plate s and the piston face so as to prevent leakage between these parts. A 85 valve stem w is rigidly fixed to the valve plate s , being in longitudinal alinement with the piston rod p and projecting through the outer end of the cylinder. On the outer end of each valve stem w is an operating lever 90 which consists of a pin x fixed laterally in 95 said stem. Keyed on the hub l is a collar y , adapted to be moved forward by a shifter lever z , which is pivoted at 2 in a bracket 3 , the latter made integral with the bearing f . The collar y is provided with radial arms 4 100 the extremities of which are curved, as at 5, and provided with slots 6, which are parallel with the longitudinal axis of the cylinders. The pins x project through said slots 6.

In Figs. 4 and 5 I have shown a preferred form of valve operating mechanism. In this form the piston rod p' is made hollow, the valve stem w' is rotatably mounted in the cylinder head, and its inner end extends into the hollow piston rod. The 110

valve s' is of the same construction and arrangement in the piston as shown in Fig. 2, but instead of being rigid on the stem w' it is provided with a key s^2 , running in a key-way w^2 of said stem. In this way, the piston is allowed free travel, but by rotating the valve stem the valve will be operated. As a means for rotating the valve stem w' I provide on its outer end a full shrouded gear 7. Each radial arm 4 is provided at its outer end with a rack 8, meshing with the gear 7, and adapted to rotate the latter and therewith the valve stem w' whenever the shifter lever z is operated. This form of valve operating mechanism is preferable because the entire device will be more compact and not take up as much space as the type shown in Fig. 1.

The general operation is as follows: The cylinders are filled with fluid, and when the shifter lever z is operated so as to open the ports in the pistons, the fluid will readily bypass from one end of the cylinder to the other, and the driven shaft e will remain stationary. However, as soon as the lever z is operated, so as to partially close the piston ports, the fluid will bypass more slowly and the reciprocations of the piston-rod will be slower, thereby transmitting a certain speed of rotation to the shaft e . When the ports are entirely closed the pistons will be held stationary at any point in the cylinders to which they may have been moved, and a constant speed equal to the speed of the drive-shaft, a , will be transmitted from the said drive-shaft, a , to the driven shaft e .

I claim:

1. In a fluid speed governing mechanism, a shaft, radial fluid cylinders fixed on said shaft, pistons reciprocable within said cylinders, a crank shaft, connections between the crank shaft and the pistons for reciprocating the latter synchronously in the same direction, means for by-passing the fluid to opposite sides of the pistons, said means comprising valve members mounted in the pistons, and operating means for said valve members, said means operable during the revolution of the cylinders.

2. In a fluid speed governing mechanism, a shaft, radial fluid cylinders fixed on said shaft, pistons reciprocable within said cylinders, a rigid piston rod connecting said pistons and provided with a yoke, a crank shaft, connections between the crank shaft and the yoke for reciprocating the pistons synchronously in the same direction, and means for by-passing the fluid to opposite sides of the pistons, said means comprising valve members mounted in the pistons.

3. In a fluid speed governing mechanism, a shaft, radial fluid cylinders fixed on said shaft, pistons reciprocable within said cylinders, a rigid piston rod connecting said

pistons and provided with a yoke, a crank shaft, connections between the crank shaft and the yoke for reciprocating the pistons synchronously in the same direction, means for by-passing the fluid to opposite sides of the pistons, said means comprising valve members mounted in the pistons, and operating means for said valve members, said means operable during the revolution of the cylinders.

4. In a device of the character described, a radial revoluble fluid cylinder, a piston reciprocable therein, said piston provided with longitudinal ports, a valve member mounted in the piston and adapted to control the opening of said ports, a rotatable valve stem projecting longitudinally through the cylinder head and slidably connected with said valve member, and means for rotating said valve stem during the revolution of the cylinder, said means comprising a member laterally movable with respect to the cylinder.

5. In a device of the character described, a radial revoluble fluid cylinder, a piston reciprocable therein, said piston provided with longitudinal ports, a valve member mounted in the piston and adapted to control the opening of said ports, a rotatable valve stem projecting longitudinally through the cylinder and slidably connected with said valve member, an operating gear on the outer end of said stem, and means for rotating said operating gear during the revolution of the cylinder, said means comprising a member laterally movable with respect to the cylinder.

6. In a device of the character described, a radial revoluble fluid cylinder, a piston reciprocable therein, said piston provided with longitudinal ports, a valve member mounted in the piston and adapted to control the opening of said ports, a rotatable valve stem projecting longitudinally through the cylinder head and slidably connected with said valve member, an operating gear on the outer end of said stem, means for rotating said operating gear during the revolution of the cylinder, said means comprising a member laterally movable with respect to the cylinder, and a rack on said member engaging with the valve operating gear.

7. In a device of the character described, a radial revoluble fluid cylinder, a piston reciprocable therein, said piston provided with longitudinal ports, a valve member mounted in the piston and adapted to control the opening of said ports, a rotatable valve stem projecting longitudinally through the cylinder head and slidably connected with said valve member, an operating gear on the outer end of said stem, means for rotating said operating gear during the revolution of the cylinder, said means comprising a member laterally movable with respect to the cyl-

under, a rack on said member engaging with the valve operating gear, and means for moving said member laterally.

8. In a device of the character described, a radial revoluble fluid cylinder, a piston reciprocable therein, said piston provided with longitudinal ports and a hollow piston rod, a valve member mounted in the piston and adapted to control the opening of said ports, a rotatable valve stem projecting longitudinally through the cylinder head into the hollow piston rod and slidably connected with said valve member, and means for rotating said valve stem during the revolution of the cylinder.

9. In a device of the character described, a radial revoluble fluid cylinder, a piston reciprocable therein, said piston provided

with longitudinal ports and a hollow piston rod, a valve member mounted in the piston and adapted to control the opening of said ports, said valve member being made with a rigid key, a rotatable valve stem projecting longitudinally through the cylinder head into the hollow piston rod and provided with a key-way in which the key of the valve member is adapted to slide, an operating gear on the outer end of said stem, means for rotating said operating gear during the revolution of the cylinder, said means comprising a member laterally movable with respect to the cylinder, a rack on said member engaging with the valve operating gear, and means for moving said member laterally.

THEODORE GENSMER.
